UNITED STATES PATENT OFFICE.

WILLIAM H. GRIPPIN, OF NEWARK, NEW YORK.

APPARATUS FOR APPLYING FILLERS TO FLOORS.

SPECIFICATION forming part of Letters Patent No. 699,307, dated May 6, 1902.

Application filed August 28, 1901. Serial No. 73,586. (No model.)

To all whom it may concern:

Be it known that I, WILLIAM H. GRIPPIN, of Newark, in the county of Wayne and State of New York, have invented a new and useful 5 Improvement in Devices for Applying Fillers, which improvement is fully set forth in the following specification and shown in the accompanying drawings.

My invention is a device for conveniently 10 applying fillers in a semifluid state to floors or other surfaces, the invention being hereinafter fully described, and more particularly pointed out in the claims.

Referring to the drawings, Figure 1 is a side 15 elevation of the device. Fig. 2 is an end elevation seen as indicated by arrow in Fig. 1, a part of the body being broken away. Fig. 3 is a plan of the device. Fig. 4 is a side elevation sectioned as on the dotted line 4 4 in Fig. 3, parts being shown in two positions by 20 full and dotted lines. Fig. 5 is a vertical cross-section of the body, taken as on the dotted line 5 5 in Fig. 4. Fig. 6 is a vertical cross-section of the body, taken as on the dotted line 25 6 6 in Fig. 4, drawn to further show the form of the rub-board. Fig. 7 is a vertical cross-section of the body as on the dotted line 7 7 in Fig. 4, further showing the form of the forward cleaner. Fig. 8 is a face view of the 30 rub-board seen as indicated by arrow 8 in Fig. 4.

A in the drawings is the body of the device, it being hollow, bottomless, and rectangular or box shape in form and preferably made of 35 sheet metal. The interior of the body is divided into a forward apartment B and a rear apartment C by a transverse inclined partition a, Figs. 3, 4, and 5, extending from side to side of the body. Within the forward apartment B is placed transversely a metal rub-board b, Figs. 3, 4, and 6, adapted to turn on a horizontal transverse axis c, having bearings in the sides of the body A, the ends of said board being adjacent to the respective 40 inner surfaces of the side walls of the body. In said apartment B is also placed a transverse cleaner d, Figs. 3, 4, and 7, adapted to rest upon the floor and to turn on a horizontal axis e, resting in the side walls of the 45 body A. In the rear apartment C of the body is placed a similar cleaner f, Figs. 2, 3, and 4, in position to meet the floor and arranged to

turn on a horizontal axis g, with bearings in the side walls of the body. The cleaners d f, like the rub-board b, extend from side to side 55 of the body within, and they are hung in such manner that both tend by gravity to meet and press the floor D, as shown in Fig. 4.

The device is provided with an operating and propelling handle h, by means of which 60 the body, which rests upon the floor, is moved hither and thither over the floor by hand in the act of applying the filler, which in a semi-fluid state is placed in the apartment B in contact with the floor. The handle is connected rigidly with the rub-board b, near its axis, and inclines backward, as shown in Figs. 1 and 4, convenient to the hand of the operator. This construction furnishes a convenient means for the operator to use the device 7c upon the floor, besides enabling him to readily tilt the rub-board as the device is moved in a backward direction in going over the floor.

The part of the rub-board below the axis e 75 inclines sharply backward, as shown in Fig. 4, so that it tends normally to press the filler hard downward against the floor. This causes the substance to enter the cracks and other crevices in the floor and fill the same and also 80 the grain of the wood. I likewise prefer to form the front or inclined operating-face of the rub-board with horizontal corrugations i to roughen said face or make it uneven. Thus formed it better holds the filler downward 85 against the floor and tends to prevent the filler from escaping upward along the face of the rub-board when in action. The lower edge of the rub-board does not touch the floor, but is held slightly apart therefrom by 90 stops r, as shown in Fig. 4, to admit a thin layer of the filler beneath it.

The lower part k of the partition a is bent sharply forward, as appears in Fig. 4, its extreme lower edge meeting the floor D adjacent to the lower edge of the rub-board when the latter is in its normal position. Also, being sharply slanted at the lower edge, as stated, it tends when the device is moved backward to press such of the filler as escapes 100 under it hard onto the floor in the same manner that the rub-board does when the device is moved forward. This part k of the partition is curved concentric with the axis b of

the rub-board and relatively so placed that when the latter is turned on its axis by means of the handle *h*, as shown by dotted lines in Fig. 4, its lower edge just clears the adjacent face of said part *k*. On account of this nearness of the edge of the rub-board with the surface of the part *k* the filler is substantially prevented from escaping back of the rub-board when the latter is tilted, as stated, the 10 filler being pressed forward by the action of the rub-board when the handle *h* is pressed downward in propelling the device forward.

The forward and rear cleaners *d f* are usually formed of metal parts or sheets *l n*, bent 15 to form and holding strips *o p* of yielding material, as leather. The manner of suspending these cleaners is such that the leather strips are held by gravity constantly in contact with the floor, serving to wipe up any 20 surplus filler that may at any time escape the rub-board. In moving the device about the floor there will at times small quantities of the filler escape the partition *a*, and so enter the apartment C, this occurring more particularly when the surface of the floor is very 25 rough or uneven; but the device is so constructed that the escaped filler caught in said apartment C will be acted upon by the part *k* of the partition and the rear cleaner *f* as 30 the rub-board and the forward cleaner *d* act on the mass in the forward apartment B.

In using this device it is ordinarily moved forward and backward by the operator in a manner similar to that in which an ordinary 35 mop is moved, and the tendency when pulling the device backward by the handle is to slightly raise the latter, while in pushing the device forward the tendency is to press downward upon the handle. These natural tendencies of the hand are important in the action 40 of this device, for when the latter is pushed forward the depressing of the handle holds the rub-board near the floor, while in drawing it back the lifting of the handle 45 turns the lower edge of the rub-board upward, and so facilitates the flowing inward of the filler ready for the next forward movement of the device.

What I claim as my invention, and desire 50 to secure by Letters Patent, is—

1. A device for applying fillers to floors, comprising a hollow bottomless case or body for receiving the filling material, a transverse movable rub-board in the body, and means to operate the rub-board and to propel 55 the device by hand, substantially as shown and described.

2. A device for applying fillers to floors, comprising a hollow bottomless body for receiving the filling material to move upon the 60 floor, a transverse pivoted rub-board in the body, inclined to the floor, and a propelling handle secured to the rub-board, substantially as and for the purpose set forth.

3. A device for applying fillers to floors, 65 comprising a hollow bottomless body for receiving the filling material, a transverse inclined rub-board resting in bearings in the body and formed with horizontal corrugations, and an operating-handle secured to the 70 rub-board to turn it upon its bearings, and to propel the device, substantially as shown and described.

4. A device for applying fillers to floors, comprising a hollow bottomless body for receiving the filling material, a transverse partition dividing the space in the body into forward and rear apartments, a rub-board and a cleaner in the forward apartment, and a cleaner in the rear apartment, with means 80 to operate the device, substantially as shown and described.

5. A device for applying fillers to floors, having a hollow bottomless body for receiving the filling material, a partition dividing 85 the space in the body, a rub-board adapted to turn upon an axis in the body, an operating-handle secured to the rub-board, the partition having a curved part adjacent to the lower edge of the rub-board and concentric 90 with the axis of the rub-board, and cleaners in the body, substantially as shown and described.

In witness whereof I have hereunto set my hand, this 23d day of August, 1901, in the 95 presence of two subscribing witnesses.

WILLIAM H. GRIPPIN.
